INVENTOR,
Jacob Ney
By *Jacob W. Bond*

ATTY.

UNITED STATES PATENT OFFICE.

JACOB NEY, OF CANTON, OHIO, ASSIGNOR TO THE V. L. NEY COMPANY,
OF SAME PLACE.

TRIP-HEAD FOR CARRIERS.

SPECIFICATION forming part of Letters Patent No. 636,834, dated November 14, 1899.

Application filed October 19, 1898. Serial No. 693,964. (No model.)

To all whom it may concern:

Be it known that I, JACOB NEY, a citizen of the United States, residing at Canton, in the county of Stark and State of Ohio, have invented certain new and useful Improvements in Trip-Heads for Carriers; and I do hereby declare that the following is a full, clear, and exact description of the same, reference being had to the annexed drawings, making a part of this specification, and to the numerals of reference marked thereon, in which—

Figure 1 is a view showing the invention applied to a hay-carrier. Fig. 2 is a detached view of the trip-head. Fig. 3 is a view showing the trip-head attached to the elevating and conveying rope. Fig. 4 is a view showing the clamp-sections detached. Fig. 5 is a view showing the clamp-sections placed together.

20 The present invention has relation to trip-heads for carriers; and it consists in the novel arrangement hereinafter described, and particularly pointed out in the claims.

Similar numerals of reference indicate corresponding parts in all the figures of the drawings.

In the accompanying drawings the invention is shown applied to a hay-elevator carrier; but it will be understood that it can be 30 applied to other overhead carriers without departing from the nature of my invention.

The object of the invention is to connect to the carrier the load connected to the elevating-block before the elevating-block has 35 reached the carrier proper.

In the accompanying drawings, 1 represents the track, which is suspended to suitable hangers in the ordinary manner and upon which the carrier 2 travels. The elevating-rope 3 is connected to the carrier 2 in the usual manner and is operated to elevate the load and move the carrier and its connected load in the usual way that hay-elevator carriers are operated or other overhead carriers. It will be understood that the carrier herein shown forms no particular part of the present invention, except that a carrier of some description must necessarily be used to carry out the purpose of the present invention. The elevating-head 4 is provided with a suitable attaching device 5, which may be

of any desired kind or style, and the top or upper portion of the elevating block or head is also provided with the registering head 6, which is for the purpose of connecting the 55 elevating-head, together with its load, to the carrier 2 when the carrier herein shown is to be operated in the ordinary manner. At a point above the elevating-head 4 is attached the trip-head 7, the top or upper end of which 60 is provided with the registering head 8, which registering head is to correspond in size and shape in all its details with the shape of the registering head 6 and is so formed that it will take the place of the registering head 6 65 when placed in the position illustrated in Fig. 1. The trip-head 7 is provided with the downwardly-extending portion or arm 9 and the eye 10. In use when it is desired to detach the carrier 2 from the stop-block 11, secured to the track 1, before the elevating-head 4 has reached a point so that the registering head 6 will engage with the carrier the trip-head 7 is connected to one of the members of the elevating-rope 3 by passing the 70 looped or doubled portion of the elevating-rope 3 through the eye 10 and over the registering head, securely connecting the registering head to the elevating-rope. It will be understood, however, that I do not desire to 75 be confined to the particular manner herein described for attaching the trip-head 7 to the elevating-rope, as other ways may be employed without departing from the nature of my invention.

85 For the purpose of insuring the registering head 8 to enter the guide portion 12 of the carrier 2 the clamp-bars 13 are provided, and for the purpose of providing a clamp that can be easily attached and detached said clamp is 80 formed in sections, and said sections hook or hinge together by means of the eye 14 and the hook 15 or their equivalents. The opposite ends of the bars 13 are provided with the semicircular grooves 16 and the recesses 17, 90 the grooves 16 being for the purpose of receiving the elevating-rope 3, and the recesses 17 being for the purpose of receiving the lug 18, which lug is preferably formed integral with the trip-head 7. After the clamp-sections 13 95 have been brought into the position illustrated in Fig. 1 the clamping-bolt 19 is placed in the 100

position illustrated in Fig. 1, which securely holds and clamps the registering head 7, so that it cannot miss the proper connection with the carrier when brought into position 5 to be connected.

It will be seen that with my improved device I am enabled to elevate the load to any desired height or point within the limits of the movements of the elevating-head 4. By 10 this arrangement a load of hay or other article need not necessarily be elevated to a point to engage the elevating-head 4 with the carrier, but may be connected to the carrier at any desired point of elevation. In the 15 mowing of hay the trip-head 7 can be adjusted so as to bring the load directly or within a few feet of the top of the hay contained in the mow, and as the mow is filled the trip-head 7 can be adjusted from time to time, so 20 that the load need only be elevated at all times a few feet above the hay or other material contained in the mow or place of deposit. When it is desired to have the load proper travel parallel with the track, the elevating-rope 3 is provided with the weight 20, 25 by which arrangement the carrier will travel, together with its load, carrying with it the weight 20. When it is desired to have the load move upward or toward the carrier, after 30 the head 8 has engaged the carrier and said carrier released from the stop-blocks on the track 1, the weight 20 is removed from the hook 21 and said hook connected to the eye 22 or its equivalent, at which time as the 35 carriage is moved upon the track 1 the elevating-rope 3 between the head 4 and the pulley 23 will be shortened as the carriage is moved away from the knot 24. It will be understood that the trip-head 7 and its different 40 parts must be so adjusted that the elevating-head 4 will not strike said trip-head. When the load has been released, the weight of the elevating-head, together with the fork or other attachment connected to the elevating-head, 45 will cause the carrier to move backward along the track until the carriage comes in contact with the stop-blocks, which connects the carriage to the track and disengages the regis-

tering head in the usual manner. For the purpose of causing the weight 20 to be elevated when said weight is connected to the elevating-rope said elevating-rope is provided with a knot, such as 24, or other stop, which prevents the rope from passing under the carrier proper, and as the pull of the elevating-rope takes effect the weight 20 will be elevated, which weight returns the carriage, together with the elevating-head.

Having fully described my invention, what I claim as new, and desire to secure by Letters Patent, is—

1. The combination of an elevating-rope and a carrier, a trip-head provided with a registering head and clamping-bars located below the registering head, substantially as and for the purpose specified.

2. The combination of a trip-head adjustably attached to an elevating-rope, clamping-bars 13, provided with the recesses 16 and 17, and a clamping-bolt located through the 70 clamping-bars and the trip-head, substantially as and for the purpose specified.

3. A trip-head adjustably attached to the elevating-rope of a carrier, and provided with a registering head corresponding with and to the registering head located upon the elevating-block, substantially as and for the purpose specified.

4. The combination of a traveling carriage, an elevating-rope connected thereto, an elevating-head carried by the elevating-rope and the trip-head 7 provided with the registering head 8, substantially as and for the purpose set forth.

5. The trip-head 7 provided with the registering head 8 and the eye 10 and an elevating-rope, substantially as and for the purpose set forth.

In testimony that I claim the above I have hereunto subscribed my name in the presence 90 of two witnesses.

JACOB NEY.
